(57) **CLAIM**

The ornamental design for a cutter, as shown and described.

DESCRIPTION

This application is related to U.S. application Ser. No. 29/836,596, entitled Cutter With Cover, filed on the same day with the same inventor and applicant-assignee as the instant application, the contents of which are hereby incorporated by reference in its entirety.

FIG. 1 is a front perspective view of a cutter;

FIG. 2 is a rear perspective view of a cutter;

FIG. 3 is a front view of a cutter;

FIG. 4 is a rear view of a cutter;

FIG. 5 is a left side view of a cutter, the right side view being a mirror image thereof;

FIG. 6 is a top view of a cutter; and,

FIG. 7 is a bottom view of a cutter.

The broken lines in the drawings illustrate portions of the cutter that form no part of the claimed design.
